ATTORNEY

UNITED STATES PATENT OFFICE.

LOUIS M. BECK, OF FORT WAYNE, INDIANA.

DRIP-CUP.

SPECIFICATION forming part of Letters Patent No. 779,200, dated January 3, 1905.

Application filed March 30, 1904. Serial No. 200,666.

To all whom it may concern:

Be it known that I, LOUIS M. BECK, a citizen of the United States of America, and a resident of Fort Wayne, in the county of Allen 5 and State of Indiana, have invented certain new and useful Improvements in Umbrella Attachments, of which the following is a specification.

This invention relates to improvements in 10 attachments for umbrellas; and the object thereof is to provide means to prevent the water from draining from the umbrella onto the floor when the umbrella is closed and carried into a building.

15 I accomplish my object by the contrivance illustrated in the accompanying drawings, in which—

Figure 1 is an elevation of the device, partly in central section and attached to the outer 20 end of an umbrella-stick. Fig. 2 is a plan view of the separable spider, and Fig. 3 is a vertical central section of the separable spider.

Similar numerals of reference indicate corresponding parts throughout the several 25 views, and referring now to the same 1 is a pliable bulb, preferably of rubber, and 2 is a spider, which is made separate from the bulb. The said bulb is greatest in diameter in its central portion and has a sleeve 3 at one end 30 and a funnel 4 in connection with its opposite end, with a contracted neck 5 intervening between the funnel and bulb proper. The inner surface of the bulb at its neck is straight and affords an annular face 6, against which 35 the ends of the arms 7 of the spider are adapted to rest.

The spider 2 is preferably composed of pliable rubber and has a central opening 8 of a size suitable for the insertion of the end of 40 an umbrella-stick 9, and the said sleeve of the bulb is also of suitable size to pass snugly over said stick and sufficiently tight as to prevent water in the bulb from leaking around said stick and through said sleeve. The advantage of constructing the spider separable 45 from the bulb becomes apparent when adjusting the device upon the umbrella-stick,

and it is also of convenience in manufacturing the device. It is the intention that the spider shall afford partial support for the bulb, and 50 to this end its connection upon the stick 9 should be substantial, and therefore the opening 8 is of such size compared with the diameter of said stick that when the stick is inserted therein the spider will become somewhat stretched and because of the contracting tendency thereof will remain in the position upon the stick to which it is adjusted.

In using the invention the spider 2 is first placed upon the stick in the position shown 60 in Fig. 1, and the bulb is then placed in position upon the said stick, so that the neck will range about the spider. When the umbrella has become wet and is closed and stood in the position indicated in Fig. 1, the water will 65 drain from the cloth top into the funnel 4 and then pass between the arms 7 of the spider into the bulb. The water may be removed from the bulb without wetting the umbrella-top by tilting the umbrella slightly and then 70 compressing the bulb, thus causing the water in the bulb to pass out through the funnel.

Having described my invention, what I claim as new, and desire to secure by Letters Patent, is—

75 In an attachment for umbrellas, a bulb having a sleeve at one end and an annular inner face near its opposite end; and a separable spider having arms adapted to rest against said face when said bulb and spider are arranged in 80 proper relation upon the stick of an umbrella, the said spider and bulb being of elastic material and each adapted to contract upon the umbrella-stick and thereby be held in place, and the said bulb being also adapted to contract 85 upon said spider and thereby become partially supported by the latter.

In testimony whereof I affix my signature in presence of two witnesses.

LOUIS M. BECK.
